PORTFOLIO

Meyer Cohen, Flushing, N. Y., assignor to Agency Paper Company, New York, N. Y., a co-partnership composed of Irwin A. Avrick and Meyer Cohen

Application March 16, 1943, Serial No. 479,333

2 Claims. (Cl. 206—63)

1

This invention relates to improvements in portfolios and more particularly to a folder for the orderly packaging and preservation of writing paper, mailing envelopes and other flat articles.

The primary object of the invention resides in a portfolio formed from a single blank of cardboard which is cut, scored, and folded in a novel manner to provide an inner pocket for receiving writing papers, envelopes, or other flat articles, there being a hinged front cover to flatly overlie the pocket and close the same together with a simple means for releasably securing the cover in a closed position.

A further feature of the invention is to provide a simple, inexpensive portfolio for the packaging and storing of flat articles, and which may contain printed indicia and colored decorations to add to the attractiveness thereof.

Other novel features of the invention will appear as the following specification is read in conjunction with the accompanying drawing, in which:

Figure 1 is a perspective view of the portfolio in closed locked position.

Figure 2 is a perspective view of the portfolio in open position.

Figure 3 is an enlarged horizontal sectional view on the line 3—3 of Figure 1.

Figure 4 is an enlarged vertical sectional view on the line 4—4 of Figure 1.

Figure 5 is a plan view of the inner side of the blank from which the portfolio is constructed.

Referring to the drawing by reference characters, the numeral 10 designates a portfolio constructed in accordance with the invention, and as illustrated in Figure 5, it will be seen that it is constructed from a single blank A of stiff foldable material such as cardboard. The blank A is scored on the spaced vertical fold scores 11 and 12, and also on spaced horizontal fold scores 13—13. The scores 11, 12, and 13 are triple scores to provide depth to the folds when the blank is folded on said fold scores to set up position for use. The fold scoring is performed from the outer surface of the blank. The scores 11, 12, and 13—13 define a rectangular shaped rear wall panel 14. Integrally connected to the top and bottom of the panel 14 along the scores 13—13 are substantially L-shaped front wall forming flaps 15—15, the foot portions 16 of which extend the full width of the panel 14. The outer end of the leg portion 17 of each L-shaped flap 15 is slit inwardly from its side edge as at 18 for a distance approximating one-half of its width to provide a locking tab 19. The tab 19 is of a length

2

less than the length of the slit and is formed with an outer rounded edge by cutting away a portion of the material. The tabs 19—19 extend in reverse directions to enable them to be brought into confronting interlocking engagement when they are folded inwardly in a manner to be presently explained to provide a front wall.

Integrally connected to the panel 14 along the score 12 is a full length side flap 20 of a width 10 less than that of the leg portions 17—17 of the L-shaped flaps 15—15. The mid-portion of the flap 20 is slit on the spaced horizontal parallel lines 21—21 outwardly from the score 12, and also is slit vertically on the line 22, the slits 21—21 being connected to the ends of the slit 22 by arcuate slits 23—23. The aforesaid slits 21—21, 22, and 23—23 cooperate to provide a continuous line of cut to facilitate the striking out of a locking flap 24 from the side flap 20. The flap 24 is 15 provided with rounded locking tabs 25—25 which may be flexed or folded on the scores 26—26 which are co-extensive with the slits 21—21. The locking flap 24 thus formed is in continuation of the panel 14.

25 Integrally connected to the panel 14 along the score 11 is a front cover panel 27 which is of rectangular shape and of a size approximating that of the rear wall panel 14. The cover panel 27 is provided with two spaced horizontal slits 28—28 which are located adjacent the free side edge thereof to respectively receive the locking tabs 25—25 when the blank is folded to set up position with the cover panel 27 closed.

To set up the blank A to form the portfolio 30 10, the end flaps 15—15 are folded inwardly on the fold scores 13—13 to a position substantially parallel to the rear wall panel 14, whereupon the locking tab ends thereof assume an overlapping relation, and by a slight flexing of the same, the slit portions 18—18 may be inter-fitted to effect an interlocking of the tabs 19—19 as best illustrated in Figures 2 and 4. The locked flaps 15—15 provide a front wall disposed in spaced parallel relation to the rear wall panel 14. 35 Next, the side flap 20 is folded inwardly on the score 12 over the locked flaps 17—17 during which operation the locking flap pops out from the body of the flap 20, and this fold formed by the score 12 together with the folds on the lines 13—13, flaps 17—17, and rear wall panel 14 co-operate to provide a pocket P into which sheets of writing paper, envelopes, and other flat articles 40 may be inserted for packaging and orderly storing. After the insertion of flat articles into the pocket P, the front cover panel 27 is folded in- 45 50 55

wardly to effect a complete closing of the pocket P and to overlie the flap 20. To lock the cover 27, the locking flap 24 is folded upwardly on the score 12 and inwardly to lie over the outer side of the cover, after which the reversely extending tabs 25-25 are flexed on the scores 26-26 and inserted through the respective slits 28-28, at which time the cover 27 is locked against accidental opening. To obtain access to the contents of the pocket P, the operator pulls outwardly on the free side edge of the flap 24, whereupon the tabs will freely slide out of the slits 28-28 and the cover may now be swung open in the manner of the cover of a book. The L-shaped flaps 17-17 when locked together provides a relatively large opening as best seen in Figure 2 to enable access to the pocket and to display portions of the contents thereof.

In practice, the outer sides of the blank A may contain printed matter appropriate to the articles to be packed into the portfolio, and colored decorations may be printed thereon to impart a more realistic portfolio appearance. Whereas the portfolio 10 will be found useful in the packaging of writing paper and mailing envelopes, the same may be used for the merchandising of other flat articles.

While I have shown and described what I consider to be the preferred embodiment of my invention, I wish it to be understood that such changes in construction, design, and material, as

come within the scope of the appended claims may be resorted to if desired.

Having thus described the invention, what I claim as new and desire to secure by Letters Patent of the United States is:

1. A portfolio comprising a single blank of cardboard which is cut and scored to provide a rectangular rear panel, top and bottom flaps joined to the rear panel at the top and bottom respectively along hinged scores and capable of being partly overlapped when folded inwardly over said rear panel parallel thereto, interlocking means on the flaps to secure them disposed over the rear panel as aforesaid, a relatively narrow side flap joined to the rear panel at one side along a hinge score so as to be folded inwardly over said top and bottom flaps when the latter are interlocked, to provide a pocket, a front cover of a size and shape corresponding to the rear wall and joined to the rear panel at its other side along a hinge score so as to be folded over all of said flaps when the latter are infolded as aforesaid, to close said pocket, and interlocking means on the rear panel and the cover for securing the cover in the closed position.

2. A portfolio as set forth in claim 1, wherein the last-mentioned interlocking means includes a member in continuation of the rear panel and said member having oppositely directed locking tabs.

MEYER COHEN.
